US00D540166S

(12) **United States Design Patent** (10) Patent No.: **US D540,166 S**
(45) Date of Patent: **** Apr. 10, 2007**

(54) **DISPOSABLE CUP LID**

(75) Inventors: **Robert W. Hollis**, Homer Glen, IL (US); **Weston S. Koennecke**, Oak Park, IL (US); **John R. Geer, III**, Downers Grove, IL (US)

(73) Assignee: **Prairie Packaging Inc.**, Bedford Park, IL (US)

(**) Term: **14 Years**

(21) Appl. No.: **29/248,898**

(22) Filed: **Sep. 8, 2006**

Related U.S. Application Data

(62) Division of application No. 29/230,074, filed on May 16, 2005.

(51) LOC (8) Cl. **09-07**

(52) U.S. Cl. **D9/447; D9/435**

(58) Field of Classification Search **D9/454, D9/450, 449, 447, 445, 441, 438, 435, 434; D7/629, 511, 510, 396.2, 392.1, 317, 391, D7/392; D3/203.2, 202; 222/555, 451.2; 220/713, 712, 270, 253, 454.1-9**

CLAIM

The ornamental design for a disposable cup lid, as shown and described.

DESCRIPTION

This application relates to the following co-pending commonly owned patent applications: “Disposable Cup Lid,” Ser. No. 29/248,892; “Disposable Cup Lid,” Ser. No. 29/248,889; “Disposable Cup Lid,” Ser. No. 29/248,885; “Disposable Cup Lid,” Ser. No. 29/248,882; “Disposable Cup Lid,” Ser. No. 29/248,886; “Disposable Cup Lid,” Ser. No. 29/248,883; “Disposable Cup Lid,” Ser. No. 29/248,888; “Disposable Cup Lid,” Ser. No. 29/248,891; and “Disposable Cup Lid,” Ser. No. 29/248,896.

FIG. 1 is a rear perspective view of a disposable cup lid of our new design, that portion of the cup lid shown in phantom is not part of the claimed design and is provided for environmental purposes only.

FIG. 2 is a top plan view of the disposable cup lid of our new design illustrated in FIG. 1, that portion of the cup lid shown in phantom is not part of the claimed design and is provided for environmental purposes only.

FIG. 3 is a bottom plan view of the disposable cup lid of our new design illustrated in FIG. 1, that portion of the cup lid shown in phantom is not part of the claimed design and is provided for environmental purposes only; and,

FIG. 4 is a rear side view of the disposable cup lid of our new design illustrated in FIG. 1, that portion of the cup lid shown in phantom is not part of the claimed design and is provided for environmental purposes only.
